(57) **CLAIM**

I claim the ornamental design for a cooker hood, as shown and described.

DESCRIPTION

FIG. 1 is a Perspective view of a cooker hood showing my new design;

FIG. 2 is another perspective view of the cooker hood of FIG. 1 shown in an alternative position;

FIG. 3 is a Front view of the cooker hood of FIG. 1;

FIG. 4 is a right-side view of the cooker hood of FIG. 1;

FIG. 5 is a Left-right side view of the cooker hood of FIG. 1;

FIG. 6 is a Top view of the cooker hood of FIG. 1; and,

FIG. 7 is a Bottom view of the cooker hood of FIG. 1. The broken lines in the drawings illustrate portions of the cooker hood that form no part of the claimed design.
